Malcolm S. Park, Mount Kisco, N. Y., assignor to The Singer Manufacturing Company, Elizabeth, N. J., a corporation of New Jersey

Application November 6, 1953, Serial No. 27,463

Term of patent 14 years

(Cl. D70—1)

To all whom it may concern:

Be it known that I, Malcolm S. Park, a citizen of the United States, residing at Mount Kisco, in the county of Westchester and State of New York, have invented a new, original, and ornamental Design for a Sewing Machine Frame, of which the following is a specification, reference being had to the accompanying drawings, forming a part thereof.

Fig. 1 represents a front elevation view of a sewing machine frame, showing my new design.

Fig. 2 represents a rear elevation view thereof.

Fig. 3 represents a top plan view thereof.

Fig. 4 represents a left-hand end view thereof.

Fig. 5 represents a right-hand end view thereof.

I claim:

The ornamental design for a sewing machine frame, substantially as shown.
